UNITED STATES PATENT OFFICE.

FRANKLIN P. BURKHARDT, OF CHICAGO, ILLINOIS, ASSIGNOR OF ONE-HALF TO FRANK STREICH, OF CHICAGO, ILLINOIS.

AUTOMATIC CARVING-MACHINE.

SPECIFICATION forming part of Letters Patent No. 758,616, dated May 3, 1904.

Application filed January 28, 1903. Serial No. 140,828. (No model.)

To all whom it may concern:

Be it known that I, FRANKLIN P. BURKHARDT, a citizen of the United States, residing at Chicago, in the county of Cook and State of Illinois, have invented a new and useful Automatic Carving-Machine, of which the following is a specification.

This invention relates to automatic carving-machines.

10 The object of the invention is to provide an automatic carving-machine which is simple in construction and efficient in operation.

The invention consists, substantially, in the construction, combination, location, and relative arrangement of parts, all as will be more fully hereinafter set forth, as shown in the accompanying drawings, and finally set forth in the appended claims.

Referring to the accompanying drawings 20 and to the various views and reference-signs appearing thereon, Figure 1 is a view in front elevation of an automatic carving-machine embodying in its construction the principles of my invention. Fig. 2 is a view in side elevation of the construction shown in Fig. 1.

Fig. 3 is a view in vertical longitudinal section on the line 3 3, Fig. 1, looking in the direction of the arrows. Fig. 4 is a view in horizontal transverse section on the line 4 4,

30 Fig. 2, looking in the direction of the arrows.

Fig. 5 is a view in vertical transverse section on the line 5 5, Fig. 2, looking in the direction of the arrows. Fig. 6 is a detail view in top plan, parts in horizontal section on the line 6 6, Fig. 5, looking in the direction of the arrows. Fig. 7 is a detached detail view in section on the line 7 7, Fig. 2. Fig. 8 is a detail view, in vertical section, on the line 8 8,

35 Fig. 4. Fig. 9 is a broken detail view in section on the line 9 9, Fig. 3. Fig. 10 is a broken detail view, in top plan, of the free end of the tracer-supporting arm. Fig. 11 is a broken detail view in section on the line 11 11, Fig. 10. Fig. 12 is a detail view, in front

40 elevation, of the free end of the tracer-arm. Fig. 13 is a detached broken detail view, in front elevation, showing the application of the principles of my invention to round or turning work. Fig. 14 is a view in section on

the line 14 14, Fig. 13, looking in the direction of the arrows.

The same part is designated by the same reference-sign wherever it occurs throughout the several views.

Referring to the accompanying drawings 55 and to the various views and reference-signs appearing thereon, A designates the supporting-base of the framework, having longitudinal tracks or ways B, upon which is mounted to travel or to be moved back and forth thereon a carriage C. Suitably mounted and journaled in bearings formed in said carriage C are vertical shafts D, to which rotation may be imparted in any suitable or convenient manner.

The upper ends of the vertical shafts D are 60 journaled in bearings formed in a bracket or frame E, as most clearly shown in Fig. 5. Suitably journaled to swing or rock about shafts D as axes are brackets F, said brackets carrying

arms G, in the outer or free ends of which are 65 journaled the rotary cutters H. These rotary cutters may be of any convenient construction and arrangement, and rotation may be imparted thereto in any convenient manner.

I have shown a simple and efficient arrangement, 70 to which, however, my invention is not to be limited or restricted and wherein belts J, operating over pulleys respectively mounted on

shafts D and the shafts carrying the rotary cutters, serve the purpose of driving or rotating said cutters. In the particular form 75 shown, to which, however, my invention is not to be limited or restricted, each bracket F carries an upper and a lower arm G, and hence in

the form illustrated as an embodiment of my 80 invention four rotary cutters are employed. Fig. 5 is a view in vertical transverse section on the line 5 5, Fig. 2, looking in the direction of the arrows. Fig. 6 is a detail view in top plan, parts in horizontal section on the line 6 6, Fig. 5, looking in the direction of the arrows. Fig. 7 is a detached detail view in section on the line 7 7, Fig. 2. Fig. 8 is a detail view, in vertical section, on the line 8 8, Fig. 4. Fig. 9 is a broken detail view in section on the line 9 9, Fig. 3. Fig. 10 is a broken detail view, in top plan, of the free end of the tracer-supporting arm. Fig. 11 is a broken detail view in section on the line 11 11, Fig. 10. Fig. 12 is a detail view, in front elevation, of the free end of the tracer-arm. Fig. 13 is a detached broken detail view, in front elevation, showing the application of the principles of my invention to round or turning work. Fig. 14 is a view in section on

the line 14 14, Fig. 13, looking in the direction of the arrows.

The same part is designated by the same reference-sign wherever it occurs throughout the several views.

Referring to the accompanying drawings 55 and to the various views and reference-signs appearing thereon, A designates the supporting-base of the framework, having longitudinal tracks or ways B, upon which is mounted to travel or to be moved back and forth thereon a carriage C. Suitably mounted and journaled in bearings formed in said carriage C are vertical shafts D, to which rotation may be imparted in any suitable or convenient manner.

The upper ends of the vertical shafts D are 60 journaled in bearings formed in a bracket or frame E, as most clearly shown in Fig. 5. Suitably journaled to swing or rock about shafts D as axes are brackets F, said brackets carrying

arms G, in the outer or free ends of which are 65 journaled the rotary cutters H. These rotary cutters may be of any convenient construction and arrangement, and rotation may be imparted thereto in any convenient manner.

I have shown a simple and efficient arrangement, 70 to which, however, my invention is not to be limited or restricted and wherein belts J, operating over pulleys respectively mounted on

shafts D and the shafts carrying the rotary cutters, serve the purpose of driving or rotating said cutters. In the particular form 75 shown, to which, however, my invention is not to be limited or restricted, each bracket F carries an upper and a lower arm G, and hence in

the form illustrated as an embodiment of my 80 invention four rotary cutters are employed.

Reference-sign K designates an arm, which I shall designate the "tracer-arm," and in the outer or free end of which is mounted and carried the tracer L, as will be more fully hereinafter set forth. The tracer-arm K is pivotally mounted to rock or swing upon a stud-bolt M, (see Figs. 4 and 5,) said stud-bolt being mounted in an arm or cross-bar N, carried by or mounted on the shafts D, as clearly 85 shown. Any convenient means may be employed for securing coincident swinging movement of the arms G and K. I have shown a

simple arrangement for accomplishing the desired object as illustrative of an operative construction wherein a yoke O is provided and arranged to form a connection between the 5 arms G and K, this yoke being pivotally connected to arm K and the two arms of said yoke being pivotally connected, respectively, to the brackets F or to the lower arms G thereof, and since each bracket F carries an upper and 10 also a lower arm G in the particular embodiment shown it will be evident that when the tracer-arm K is rocked or swung a coincident and similar rocking or swinging movement is imparted to the cutter-carrying arms G.

15 As above stated, rotation may be imparted to the vertical shafts D in any suitable or convenient manner. I have shown a simple arrangement of driving mechanism as an illustrative embodiment of an operative means, 20 but to which I do not desire to be limited or restricted and wherein is employed a drive-shaft P, adapted to receive rotation through belt Q or otherwise from any convenient source. A belt R, driven from shaft P, operates over a pulley S on a shaft T, and the vertical shafts D are driven from shaft T through the intermeshing bevel-gears A', and the rotation thus imparted to the shafts D is transmitted to the rotary cutters H through 25 the belts J, as above explained.

30 Swinging or rocking movements may be imparted in many specifically different ways to the tracer and cutter carrying arms K and G, so as to cause the tracer and cutters to sweep over the pattern and work. I have shown a simple arrangement for accomplishing the desired object which I have found efficient, but to which I do not desire to be limited or restricted and wherein the tracer-arm 35 K is provided with an extension or projecting part B', to the free end of which is pivotally connected one end of a link C', the other end of said link being pivotally connected eccentrically to a disk or wheel D'. If desired and 40 in order to insure coincident rocking movements of the cutter-supporting arms and to prevent independent vibrations, the free ends of the cutter-supporting arms may be connected together by pivoted links H'. If desired and 45 in order to adjustably vary the limit of throw or sweep of rocking movement of the tracer and cutter arms, the point of eccentric connection of link C' to the disk or wheel D' may be adjusted radially with respect to 50 said disk or wheel, and a way or track is shown in Figs. 4 and 5 whereby this adjustment may be effected.

55 Rotation may be imparted to disk or wheel D' in many different ways. I have shown a 60 simple arrangement, to which, however, I do not desire to be limited or restricted, and whereby the speed of swinging movement may be adjusted or varied at pleasure. In the form shown the wheel or disk D' is driven by 65 the frictional contact with the face thereof of

a friction drive-wheel E', mounted upon a shaft F', upon which is also mounted a gear G', intermeshing with and driven from a worm-gear H', mounted on and rotating with shaft T. In order to vary or adjust the speed of 70 swinging or rocking movement of the tracer and cutter arms, provision is made for varying the speed at which the disk or wheel D' rotates. This result may be accomplished in many different ways. I have shown one arrangement, which is simple and efficient and wherein provision is made for shifting or moving the driving friction gear or wheel E' nearer to or farther from the axis of the driven wheel or disk D'. To secure this adjustment, 75 gear or wheel E' is splined or keyed to shaft F', but is free to slide therealong. A pawl or latch J' is pivotally mounted on a handle K' (see Fig. 9) and is provided with a hooked end arranged to engage a collar or flange on 80 the hub of gear or wheel E'. The pawl or latch J' is provided with a tooth L', arranged to be received in one or another of notches or recesses formed in a bar or part M', carried by or forming part of the traveling carriage 85 C. Thus it will be seen that by rocking the pawl or latch J', so as to disengage the tooth L' thereof from one of said notches, the friction drive wheel or disk E' may be shifted along shaft F' to any desired point, where it 90 will be locked by causing the tooth L' to enter the corresponding notch or recess. This rocking movement of pawl or latch J' to disengage tooth L' should not be of sufficient extent to disengage the hooked end of such pawl or 95 latch from the flange or collar on the hub of gear-wheel E'. In this manner the drive-wheel E' may be adjusted nearer to or farther from the axis of rotation of friction disk or wheel D', thereby securing the desired adjustments of speed of rocking or swinging movements to be imparted to the tracer and cutter carrying arms. As above indicated, however, 100 my invention is not to be limited or restricted to the specific character of mechanism employed for imparting swinging or rocking movement to the tracer and cutter carrying arms nor to the specific details of construction shown and described for securing adjustment 105 of the rate of speed of swinging or rocking movement of said arms, as many variations and changes in the details and arrangement 110 would readily occur to persons skilled in the art and still fall within the spirit and scope 115 of my invention.

120 In the operation of a carving-machine embodying the principles of my invention it is desirable to readily advance or move the work and pattern or the tracer and cutters, so as to effect a progression of the cutters and tracer 125 over the surface of the work and pattern. In the particular form, construction, and arrangement of machine which I have shown as an embodiment of my invention, but to which I do not desire to be limited or restricted, I 130

make provision for advancing the carrier upon which the cutters and tracer are mounted or supported, and in carrying out my invention I propose to impart a step-by-step feed or advancement of the carrier C along its tracks or ways B, and in the efficient operation of the machine it is desirable that the advancing or feeding movement of the cutters be accomplished while the cutters are in the extreme 5 limits of their swinging or rocking movements, and hence at a time in the operation of the cutters when they are not in engagement with their work. Thus in practice the work is supported upon a suitable table beneath the 10 path traversed by the cutters during their rocking or swinging movement, and consequently at each extreme limit of the swinging movement of the cutter-arms the cutters may be carried slightly beyond the edges of the 15 work. I therefore make provision for effecting the advancing or feeding movement of the cutter-arm-supporting carriage while the cutter-arms are in or occupy the extreme limit of their rocking or swinging movements. To 20 this end I employ feed screws or screw-rods N' O', operating through nuts P', connected to or forming part of the traveling carriage C and bracket E. These screw-rods N' O' are 25 geared to rotate together or in unison in any 30 suitable manner—as, for instance, by means of a shaft Q', carrying bevel-gears R', respectively meshing with bevel-gears S' on said screw-rods N' O', so that when rotation is imparted to one of said screw-rods such rotation 35 is transmitted to the other. Any suitable or convenient means may be employed for imparting a step-by-step rotary movement to one or the other of these screw-rods; but in the provision of such means it is desirable, as 40 above explained, to provide for effecting this rotary movement at the limits of the swinging or rocking movements of the cutter-carrying arms. To accomplish this result I mount upon the rod N', for instance, adjacent 45 to each end thereof, a pendulum A², the pendulums being connected together by means of a rod B². Each pendulum is provided with a weight C², which serves to hold the pendulum-arms in a vertical position or to return 50 said arms to such position when displaced therefrom. Suitably secured by spline or key or otherwise to the screw-rod N' adjacent to the pendulum-arms A² are gear-wheels D², with the teeth of which engage pawls E², pivotally 55 mounted upon the pendulum-arms A². These gear-wheels may have any desired number of teeth, depending upon the speed of the feed movement desired. Thus when the pendulum-arms A² are locked in one direction the 60 engagement of pawls E² with the teeth of gears D² will impart a rotative movement to said gears, and hence also to the screw-rod N', such rotative movement being transmitted to the screw-rod O', as above explained, and by 65 reason of the fact that the pendulum-arms A²

are connected together by rod B² it will be seen that said pendulum-arms move together or in unison. Suitably mounted in ways or seats formed in one or the other of the upper cutter-carrying arms G are fingers F². In practice 70 these fingers are preferably carried by adjustable slide-blocks G², as clearly shown in Fig. 6, said blocks being adjustably mounted in seats or ways formed to receive the same in arms G². In practice I arrange one of the fingers F² on one side of the pivot-shaft D and the other finger on the opposite side of the pivot-shaft D. From this arrangement it will be readily seen that when arm G is rocked or swung in one direction and as it arrives at or approaches 75 the limit of its swinging movement one of the fingers F² will engage rod B², and thereby swing the pendulum-arms A², and when the arm G rocks or swings to the opposite limit of its swinging movement the other finger 80 will engage rod B², thereby rocking or swinging the pendulum-arms in the other direction, and in either case a rotative movement is imparted to the feed-screw rods N' O'. By shifting the stop-fingers F² from one to the other 85 of the cutter-supporting arms G and by suitably reversing the pivoted pawls E² it will be readily seen that the direction of the feed movement imparted to the carriage C and the parts supported thereby may be readily reversed, thereby enabling the cutters to 90 progress in either direction during the swinging movements thereof. This I regard as an important feature of my invention, as it enables me to continuously operate the machine in both 95 directions—that is, after the cutters have progressed to the full length of the work in one direction the movement may be reversed and work accomplished during the reverse traverse or travel of the cutter-supporting carriage—100 and it will be seen that the weights C² of the pendulum-frame after being displaced under the influence of the engagement of a finger F² when the cutter-arms are rocked in one direction will return the pendulum-frame to a 105 central position upon the return movement of the cutter-supporting arm, thereby drawing the pawls or dogs E² idly over one or more of the teeth of gears D², according to the desired speed of the feed. 110

From the foregoing description it will be observed that I provide a construction and arrangement wherein longitudinally-reciprocating rotating shafts are avoided. I have found in my experience with carving-machines that 115 where longitudinally-reciprocating rotating shafts are employed dust and dirt or particles of the material detached by the cutters will collect or accumulate on the bearing-surfaces of the reciprocating rotating shafts and cause 120 rapid wear thereof and looseness or lost motion, which is exceedingly undesirable, as any wear or looseness detracts from the finished character of the work produced and prevents sharply-defined duplications of the pattern, 125 130

which becomes noticeable as the wear or lost motion or looseness of the parts increases, thereby destroying or materially detracting from the beauty of the finished product. This objection is especially present where the cutter-shafts are driven at a comparatively high rate of speed, the wear in such cases being rapid, necessitating frequent, in fact almost constant, renewals of the bearings or bushings, and hence greatly adding to the expense of maintenance of the machine, and these objections are obviated in a machine embodying the principles of my invention as herein set forth.

- 15 It may sometimes be desirable to produce a carving of increased or decreased relative proportions with respect to the size of the pattern employed. Where the tracer is arranged in axial alinement with the rotating cutters and with the same or coincident extent of lateral swinging movements, the reproductions or work are coextensive or of equal size with respect to the pattern over which the tracer operates. If, however, the tracer be adjusted 25 in one direction or the other in the longitudinal direction of feed or progression of the cutters and tracer so as to be in advance or to the rear of the axial line of the cutters or with reference to a plane containing the cutters, it 30 will be obvious that the relative lengths of the tracer and cutter-carrying arms is varied, thereby enabling the cutters to magnify or to minimize the work produced with reference to the pattern, producing a carving of larger 35 or smaller dimensions relative to the pattern. To accomplish this result, I propose to adjustably mount the tracer L in the outer or free end of the tracer-arm K, and I have shown in Figs. 10, 11, and 12 a simple and convenient 40 arrangement for securing such adjustment. In this construction, to which, however, I do not desire to be limited or restricted, I support the tracer L in a bracket or frame J², arranged to be adjusted longitudinally with respect to the arm K in any suitable manner—as, for instance, by a hand-wheel K² and rod L², tapped or threaded through an opening in bracket J². The tracer is arranged to project 45 or extend through elongated slots M² in a housing N², supported at the free end of the tracer-arm K. Nuts O² serve to efficiently clamp and hold the tracer in its adjusted position. In this manner the desired adjustments of the tracer relatively to the plane in 50 which the cutters operate may be readily effected.
- Ordinarily in automatic carving-machines the work and pattern are clamped or held on suitable tables, and during the relative trav- 60 erse or feed of such tables and the frame supporting the cutters longitudinal movements are imparted to the cutters. This necessitates the provision of longitudinally-reciprocating rotating cutter-shafts, as above explained, and 65 in addition imposes upon the pattern the work

of raising and lowering the cutter-shafts and frequently their supporting-frames. In accordance with the principles of my invention I propose to avoid this necessity, and in carrying out my invention I propose to mount the 70 cutters, as above explained, upon arms to which only lateral rocking or swinging movements are imparted, and I propose to mount the work, as well as the pattern, upon a balanced table, and I propose to provide a friction mechanism for securing the desired vertical movements of the table against any suitable tension and in accordance with the design of the pattern, so as to enable the work to be raised and lowered or to be moved toward and 80 from the cutters instead of moving the cutters toward or from or raising or lowering the cutters with reference to the work.

In accordance with my invention I provide a work and pattern supporting framework, 85 including a frame having bearing-sleeves P², arranged to slide vertically upon the frame-posts Q². Carried by these sleeves P² are the work-supporting tables R², having side bars in which are formed tracks or ways (indicated 90 at S²) extending lengthwise with respect to the machine, adapted to receive the work, (indicated at A³.) If desired, any suitable form of clamp may be employed for clamping the work to the working table. The tables and 95 their supporting-frames and sleeves are yieldingly supported upon springs B³, arranged, as shown, to surround the frame-rods Q².

C³ designates the supporting table for the pattern D³, the pattern-supporting table C³ 100 being provided with ways S³, similar to the ways formed in the work-supporting tables R² and for a similar purpose, as above explained. The pattern-supporting table C³ is suspended from the lower work-supporting 105 table R² at the corners thereof by pivoted table. Adjacent to each of its corners the pattern-supporting table is provided with shoes E³, (see Figs. 1, 4, and 8, especially Fig. 4,) 110 arranged to form guideways to receive and embrace endless friction bands or chains G³. 115 These friction bands or chains are preferably formed of connected blocks in the form of endless sprocket - belts arranged to operate vertically around toothed sprocket-wheels H³ J³, the sprocket - wheels H³ being mounted 120 upon shafts K³, and the sprocket - wheels J³ being mounted upon shafts L³. Any suitable means may be provided for imparting rotation to the shafts L³—as, for instance, by means of a counter-shaft M³, suitably driven 125 from any convenient source and carrying worms N³, respectively arranged to intermesh with and to drive gears O³ on the shafts L³ at a constant speed. The arrangement is such that the inner vertical runs or legs of the 130

endless friction-belts G^3 are on both sides of the pattern-carrying table moved downwardly, as indicated by the arrows in Figs. 1 and 8, and these downwardly-moving portions 5 of the endless belts operate through the guide-shoes F^3 of the pattern carrier or table. From this construction it will be readily seen that when the pattern-table is moved either laterally or endwise or in any other except a directly-vertical direction the bearing-surfaces of the shoes F^3 will engage the downwardly-moving portions of the friction-belts on one or both sides of the pattern-table, according 10 to the direction in which the pattern-table is swung, thereby causing a frictional engagement of the traveling friction-belts with the bearing-surfaces of the shoes F^3 , and hence moving the pattern-table downwardly, and as the pattern-table moves downwardly the work-supporting tables R^2 , upon or from which the pattern-table is suspended through the links E^3 , are correspondingly moved or drawn 15 downwardly upon the rods Q^2 as guides, as will be clearly understood, and against the action of springs B^3 , the tension of said springs tending to elevate or restore the work-supporting and pattern-supporting tables. The 20 operation of this part of my invention will now be understood. The tracer L , operating over a pattern D^3 , encountering a raised surface on the pattern during the lateral swinging movements of the tracer-arm K , will exert a lateral pressure upon the pattern in proportion to the abruptness or acuteness of the 25 raised surface in contact with which the tracer-tool moves or which said tool encounters, thereby exerting a lateral pressure depending in direction of application upon the direction in which the tracer-arm is moving laterally as well as the shape and contour of 30 the pattern-surface over which the tracer is moving, and such lateral pressure exerted upon the pattern and through it upon the pattern-supporting table will press the pattern-supporting table in one direction or the other, 35 as the case may be, thereby carrying the guide-shoes F^3 on one side or the other thereof or on both sides, as the case may be, into bearing against the constantly-traveling endless friction-belts, thereby lowering the pattern-supporting table as well as the work-supporting 40 tables. This result is secured, as above indicated, in whatever direction the pattern-supporting table is pressed by reason of the fact that the shoes F^3 embrace the traveling friction-belts on three sides, as is most clearly 45 shown in Fig. 4. Therefore whether the pattern-supporting table is moved transversely or laterally or is moved endwise or is pressed 50 in any direction out of its normal position some one or another of the shoes F^3 will engage some portion of a corresponding traveling friction-belt. This I regard as a most important feature of my invention, for the reason 55 that thereby I am enabled to produce ex-

act duplications of the pattern without the employment of longitudinally-reciprocating rotating shafts. Moreover, by this construction the tracer-tool is relieved of the work of raising and lowering the cutter-supporting 70 frame, but is only required to produce sufficient lateral or longitudinal pressure on the pattern-supporting table to effect engagement of the shoes with the traveling friction-belts, the work of raising and lowering the pattern 75 and work supporting tables being accomplished by the friction-belts, which are positively driven in co-operation and acting in opposition to the tension of springs B^3 .

If desired, and preferably, the shoes F^3 are 80 made in separate sections, as clearly indicated in Fig. 4, said sections being adapted to be bolted or otherwise clamped or secured together and in hugging relation with their co-operating friction-block belts. Thus by adjusting the clamping-screws of said shoe-sections said sections may be adjusted into such relation with respect to the friction-belts as to maintain any desired degree of contact therewith, while permitting the belts to travel 90 or move therethrough, and consequently the friction mechanism becomes sensitive in the accomplishment of its work to very slight pressure of the pattern-support, thereby enabling the machine to accurately reproduce 95 delicate designs or patterns.

If desired, and preferably, a bearing or resistance block may be arranged on the opposite side of the run or leg of the friction-belt from the shoe F^3 , as indicated at A^9 , Fig. 8, 100 to take the thrust of the shoe and to secure an efficient operation of the friction mechanism.

In machines of the character to which my invention relates it is important to maintain an accurate balance between the weight of the 105 work-supporting and pattern-supporting tables with the added weight of the work and pattern imposed thereon and the tension of springs B^3 , so as to enable sensitive work to be accomplished—that is, so as to enable the friction drive mechanism above described to readily respond to slight variations in the pressure exerted by the tracer upon the design or configurations of the pattern. When this accurate balancing is attained with a certain 110 weight of work or pattern imposed upon the tables, that equilibrium or balance is deranged in case the weight of the work or pattern should be increased or decreased. For instance, when the machine is employed for 115 wood-carving and the equilibrium or balance is adjusted for light wood that equilibrium or balance is deranged when heavy wood—such, for instance, as oak, walnut, or the like—is to be operated on. It is therefore desirable in 120 order to readily and adjustably maintain an equilibrium in proportional relation to the weight of the work or to the tension of springs B^3 to provide means for adjustably varying 125 this proportional relation. To this end I em- 130

ploy a scale device P^3 , one member of which is connected to a spring Q^3 , (see Figs. 1 and 2,) the other member of said scale device being suitably connected through a link R^3 and 5 an ordinary turnbuckle S^3 to a crank-arm T^3 upon a shaft A^4 , suitably journaled in upright standards B^4 . In the particular form shown I mount upon each end of each of the shafts A^4 a segment-gear C^4 , arranged to mesh with 10 racks D^4 , formed on or secured to the sleeves P^2 of the work-supporting tables. In this manner the tension of springs Q^3 , operating through the crank-arm T^3 and the scale devices, supplements the tension of springs B^3 , 15 and consequently when the weight of the work varies by suitably adjusting the turnbuckles S^3 equalization or a balanced proportional relation between the weight of the work and the tension of the supporting-springs may 20 be readily secured through the engagement of the segment-gears C^4 and racks D^4 , the scale attachment indicating the degree of adjustment necessary for the turnbuckles S^3 to maintain the proportional or equalized balanced 25 relation, as above described. It will be observed that each of the four sleeves P^2 is provided with a rack D^4 and that the shafts A^4 on opposite sides of the machine extend parallel to each other. By this construction I secure 30 absolute coincidence of movement of the table-supports and without danger of binding of the sleeves upon their guide-rods.

I have described that the friction-belts G^3 may be positively driven from any suitable or 35 convenient source. I have shown a simple arrangement utilizing the drive-belt R . As above explained, this drive-belt is driven from a pulley or shaft P , the latter receiving rotation from any suitable or convenient source of 40 power, and this drive-belt operates around pulley S on shaft T to drive the gearing through which the cutters H are rotated and also the gearing through which the lateral swinging or rocking movements are imparted 45 to the cutter and tracer supporting arms. This belt R is also arranged to operate over a pulley E^4 on a shaft F^4 . On this shaft F^4 (see the dotted lines in Fig. 4) is mounted a pulley G^4 , and a belt H^4 , operating thereover and 50 through a pulley J^4 on shaft M^3 , which drives the latter, and through the gears N^3 O^3 , as above described, are positively driven the friction-belts G^3 . It is obvious, however, that any other suitable or convenient form of driving 55 mechanism may be readily devised by one skilled in the art without departing from the spirit or scope of my invention.

In Figs. 13 and 14 I have shown my invention as applied to carving round or turned 60 work and employing a round or turned pattern. In this arrangement I employ rotatable centers K^4 , co-operating with tail-screws L^4 , between which the work, as well as the pattern, may be clamped, and by imparting rotation to 65 the centers K^4 the work and pattern may be

rotated. Thus I have shown a pair of centers and tail-screws for each piece of work and also a pair for the pattern. The tail-screws are carried by bars M^4 , the ends of which may be slid into the side guides S^2 of the work 70 and pattern supporting tables and suitably clamped in position. When it is desired to operate on panel or plane work, the bars M^4 may be moved to one end or the other of the work or pattern supporting tables or removed 75 entirely therefrom, as may be desired. Rotation may be imparted in any suitable or convenient manner to the center K^4 . I have shown an arrangement wherein on the shafts of the centers are mounted sprocket-gears N^4 , over 80 which is arranged to operate a sprocket-chain O^4 , and hence by imparting positive rotation to one of the centers—as, for instance, the center of the pattern-supporting table—through a sprocket-drive-chain P^4 , driven from 85 a shaft Q^4 from any suitable or convenient rotating or driving part of the machine, all of the centers are coincidentally rotated. If desired, and in order to produce left-handed as well as right-handed work from the same pattern, the lead of the sprocket-chain O^4 may be suitably changed. For instance, and as indicated in Fig. 13, idler-sprockets R^4 may be arranged on opposite sides of the drive-sprocket N^4 of the pattern-center. Now by 90 leading the drive-chain O^4 around the outside of one of the idler-sprockets R^4 , thence up over and around the sprocket N^4 of the pattern-center, thence down underneath and around the other idler R^4 , and thence around the drive-sprockets of the work-centers, it will be readily seen that the work will be driven in the opposite direction with reference to the direction of rotation of the pattern, thereby producing right or left hand work, as the case 95 may be, with the same pattern. Of course it will be understood that with round or turned work lateral vibrations need not be imparted to the tracer and cutters.

From the foregoing description it will be 100 readily seen that a machine embodying the principles of my invention embodies a construction in which the cutters are rotated and are swung or vibrated laterally; but the rotating cutter-shafts are not reciprocated longitudinally nor are the cutter-supporting arms raised or lowered. It will also be seen that a feed is imparted to the carriage upon which the cutter-supporting and tracer-supporting arms are mounted and that this feed is a step-by-step feed, the feed movement being accomplished only at the limits of the lateral swinging movement of the cutter-supporting arms. In other words, the arcs described by each cutter upon the swinging movements thereof 115 are of the same radius; but the center or axis about which the cutters swing is constantly advanced step by step. By this arrangement it will be seen that the paths or arcs described by the cutters during their laterally-swinging 120

125 130

movements approach or converge toward each other at the ends thereof or at the limits of swinging movements imparted thereto. This enables me to secure fine and accurate duplications of the pattern. Moreover, by this arrangement the cutters always operate upon the material laterally, and consequently I am enabled to secure more sharply defined curved surfaces in the work. It will also be seen that the automatic step-by-step feed movements imparted to the carriage upon which the cutters are supported may be reversed, so as to enable the cutters to operate when traveling in either direction lengthwise of the machine. It will also be seen that I secure absolute coincidence of lateral swinging movement of the cutter and tracer carrying arms and that the speed of lateral swinging movement may be adjustably varied as desired or according to the character of the work to be produced. It will also be seen that the tracer may be adjusted toward or away from the plane containing the cutters, thereby enabling me to produce work which is either an exact duplication in size of the pattern or which may be larger or smaller than the pattern. It will also be seen that I secure an efficient equalization or balancing of the work and pattern supporting tables and am enabled to adjust this balanced condition in proportional relation to the weight of the work being operated upon. It will also be observed that the work of moving—that is, of lowering—the tables and of raising the same is accomplished frictionally, and thus the tracer is relieved from accomplishing this result except to impart a lateral pressure to the pattern and through the pattern to the pattern-supporting table. It will also be seen that both right and left hand cylindrical or round work may be accomplished with the same pattern and that the machine may be very readily converted or employed for flat or for round or turned work at pleasure. It will also be seen that the cutters are arranged to operate in constant relation with respect to the grain of the material being operated upon, thus avoiding the danger of splintering and spoiling the work.

It is believed that the operation of the machine will be readily understood from the foregoing description when taken in connection with the accompanying drawings.

It is to be understood that many variations and changes in the details of construction and arrangement would readily occur to persons skilled in the art and still fall within the spirit and scope of my invention. I do not desire, therefore, to be limited or restricted to the exact construction and arrangement of parts shown and described; but,

Having now set forth the object and nature of my invention and a construction embodying the principles thereof, what I claim as new and useful and of my own invention, and desire to secure by Letters Patent, is—

1. In a carving-machine, and in combination with work and pattern supports, a carriage, tracer and cutter arms supported thereon, means for laterally swinging or rocking said arms, and means for automatically advancing said carriage relatively to said work and pattern supports, as and for the purpose set forth. 70

2. In a carving-machine, and in combination with work and pattern supports, a carriage, tracer and cutter carrying arms supported upon said carriage, means for laterally vibrating or swinging said arms, and feed mechanism for said carriage, said feed mechanism being actuated automatically when said swinging arms approach the limits of their swinging movement, as and for the purpose set forth. 75 80

3. In a carving-machine, and in combination with work and pattern supports, a carriage, tracer and cutter supporting arms carried thereby, means for laterally and coincidentally swinging or rocking said arms, feed mechanism for advancing said carriage, and means arranged in the path of swinging or 85 90 rocking movement of said arms for operating said feed mechanism, as and for the purpose set forth.

4. In a carving-machine, and in combination with work and pattern supports, a carriage, tracer and cutter supporting arms mounted thereon, means for laterally vibrating or swinging said arms, feed mechanism for said carriage, ratchet mechanism for imparting a step-by-step operation to said feed 95 100 mechanism, and means arranged in the path of swinging or rocking movement of said arms for actuating said ratchet mechanism at the limit of swinging movement of said arms, as and for the purpose set forth. 105

5. In a carving-machine, and in combination with work and pattern supports, a carriage, shafts journaled therein, cutter-arms mounted to swing about said shafts as axes, a tracer-arm, connections between said tracer 110 and cutter arms to secure coincident lateral vibration or swinging movement, means for laterally swinging said tracer-arm, feed-screws for advancing said carriage, and ratchet mechanism arranged in the path of swinging movement of one of said arms for operating said feed-screws, as and for the purpose set forth. 115

6. In a carving-machine, and in combination with work and pattern supports, a carriage, tracer and cutter supporting arms 120 mounted thereon for lateral swinging or rocking movement, a feed-screw for said carriage, and automatic reversible ratchet mechanism arranged to be operated by the swinging movement of one of said arms for operating said feed-screw, as and for the purpose set forth. 125

7. In a carving-machine, and in combination with pattern and work supports, a carriage, tracer and cutter supporting arms carried thereby, means for laterally swinging or 130

rocking said arms, a feed-screw for said carriage, ratchet mechanism for actuating said screw, and stops carried by one of said arms arranged to actuate said ratchet mechanism at each limit of movement of said arm, as and for the purpose set forth.

8. In a carving-machine, and in combination with work and pattern supports, a carriage, tracer and cutter supporting arms mounted thereon, means for imparting lateral swinging or rocking movement to said arms, stops mounted upon one of said arms and on opposite sides of the axis about which said arm swings or rocks, feed mechanism for said carriage, and means arranged to be engaged alternately by said stops for actuating said feed mechanism, whereby said feed mechanism is actuated at the limits of swinging movement of said arm in both directions, as and for the purpose set forth.

9. In a carving-machine, and in combination with pattern and work supports, a carriage, tracer and cutter supporting arms mounted thereon, means for imparting lateral swinging or rocking movement to said arms, a feed-screw for said carriage, gear-wheels mounted on said screw, pendulum-arms mounted to swing loosely upon said screw, and carrying pawls, a rod connecting said pendulum-arms, and stops carried by one of said arms and arranged to engage said rod to actuate said pawls, as and for the purpose set forth.

10. In a carving-machine, and in combination with work and pattern supports, a carriage, tracer and cutter supporting arms carried thereby, means for laterally rocking or swinging said arms, a feed-screw for said carriage, weighted pendulum-arms loosely mounted upon said screw and carrying feed-pawls, gear-wheels mounted upon said screw, and with which said pawls coöperate, a rod connecting said weighted pendulum-arms, and stops adjustably mounted upon one of said arms and on opposite sides of the axis of rotation thereof, and arranged to engage said rod to rock or swing said pendulum-arms, as and for the purpose set forth.

11. In a carving-machine, and in combination with work and pattern supports, tracer and cutter supporting arms, means for advancing said tracer and cutter supporting arms over the pattern and work gearing for laterally swinging or vibrating said arms, and means for adjustably varying the speed of the lateral swinging or rocking movements of said arms, as and for the purpose set forth.

12. In a carving-machine, and in combination with work and pattern supports, tracer and cutter supporting arms, connections between said arms to secure coincident lateral vibration thereof, said tracer-arm having an extension, gearing connected to said extension for imparting lateral vibration to said arm, and means for varying the speed of operation

of said gearing to vary the rate of speed of vibration or rocking movement of said arms, as and for the purpose set forth.

13. In a carving-machine, and in combination with work and pattern supports, pivotally-mounted tracer and cutter supporting arms, connections between said arms whereby lateral swinging movement imparted to one of said arms is transmitted coincidently to the other of said arms, said tracer-arm having an extension, a driving-disk, a link pivotally connected to said extension at one end and eccentrically to said disk at the other end, and an adjustable friction drive-wheel coöperating with said disk, as and for the purpose set forth.

14. In a carving-machine, and in combination with work and pattern supports, pivotally-mounted tracer and cutter carrying arms, connections between said arms to secure coincident lateral swinging or rocking movement thereof, said tracer-arm having an extension beyond the point of its pivotal support, a disk, a link eccentrically connected at one end to said disk and at the other end to said extension, a drive-shaft, a friction-wheel mounted thereon to rotate therewith, but capable of longitudinal movement along said shaft, and arranged to coöperate with said disk to drive the latter frictionally, means for adjusting the position of said drive-wheel toward and from the axis of said friction-disk, and means for locking said wheel in adjusted position, as and for the purpose set forth.

15. In a carving-machine, and in combination with pattern and work supports, a carriage, shafts supported therein, gearing for driving said shafts, cutter-supporting arms sleeved to rock about said shaft, and carrying cutters, means for driving said cutters from said shaft, a pivotally-mounted tracer-arm, connections between said tracer and cutter supporting arms to secure coincident lateral swinging movement thereof, means connected to said tracer-arm for laterally swinging or rocking the same about its pivot, feed mechanism for moving said carriage relatively to said work and pattern supports, and including feed-screws, gearing between said feed-screws to secure coincident operation thereof, and means arranged in the path of swinging movement of one of said arms for automatically operating said feed mechanism, as and for the purpose set forth.

16. In a carving-machine, and in combination with work and pattern supports, and laterally-vibrating cutters, said cutters arranged to vibrate in approximately the same plane a tracer, a supporting-arm therefor, connections between said arm and the supports for said cutters to secure coincident laterally-vibrating movements of said arm and supports, and means for adjusting the position of the tracer toward and from the plane in which said cutters laterally vibrate, as and for the purpose set forth.

17. In a carving-machine, and in combination with work and pattern supports, and laterally vibrating or swinging tracer and cutter supporting arms, a tracer mounted in said tracer-supporting arm, to vibrate in the plane in which the cutters vibrate, means for adjusting said tracer relatively to said arm to vary the position of said tracer with reference to the plane or path of lateral vibration of the

5 cutters, said cutters being arranged to vibrate in approximately the same plane and means for locking said tracer in adjusted position, as and for the purpose set forth.

18. In a carving-machine and in combination with work and pattern supports, tracer and cutter supporting arms, and means for laterally swinging or rocking said cutters carried in said cutter-supporting arms, said cutters arranged to swing or move in approximately the same plane, a slotted housing carried in the free end of said tracer-supporting arm, a block or casting mounted in said housing and carrying a tracer, said tracer extending through the slots in said housing, means 20 for adjusting said block or casting in said housing and longitudinally with respect to said tracer-supporting arm to adjust the tracer toward or from the plane in which the cutters vibrate laterally, and nuts for locking said 25 tracer in its adjusted position, as and for the purpose set forth.

19. In a carving-machine, and in combination with tracing and cutting mechanism, and means for operating the same, pattern and work supports, means for yieldingly supporting the same, and friction mechanism for moving said supports against the action of said yielding supporting means, as and for the purpose set forth.

40 20. In a carving-machine, and in combination with tracer and cutter mechanism, and means for operating the same, a pattern and work support, means for yieldingly supporting the same, and positively-actuated friction mechanism for moving said supports against the action of said yielding means, as and for the purpose set forth.

21. In a carving-machine, and in combination with tracing and cutting mechanisms, and means for operating the same, work and pattern supports, said pattern-support being pivotally suspended from said work-supports, friction drive mechanism arranged adjacent to said suspended pattern-support, and operating when said pattern-support is pressed thereagainst to move said supports, and a spring arranged to oppose said movement, as and for the purpose set forth.

60 22. In a carving-machine, and in combination with tracing and cutting mechanisms, and means for operating the same, a work-support, a pattern-support pivotally suspended therefrom, positively-driven friction-belts, shoes carried by said pattern-support and co- 65 operating with said friction-belts, whereby

when said pattern-support is pressed toward the friction-belts said shoes engage said belts and said support is moved, and means for yieldingly opposing said movement, as and for the purpose set forth.

70

23. In a carving-machine, and in combination with tracing and cutting mechanisms, and means for operating the same, a work-table, a pattern-supporting table suspended from said work-table, and carrying shoes, positively-driven friction-belts arranged to be embraced by said shoes, and a spring arranged to oppose the action of said friction-belts, as and for the purpose set forth.

75

24. In a carving-machine, and in combination with tracing and cutting mechanisms, and means for operating the same, work and pattern supporting-tables, springs arranged to support said tables, positively-driven friction-gearing arranged on opposite sides of said pattern supporting table and operating when said table is pressed against said gearing to move said table against the action of said supporting-springs, and connections between said pattern and work supporting tables, as and for the purpose set forth.

80

25. In a carving-machine, and in combination with tracing and cutting mechanisms, and means for operating the same, work and pattern supporting tables, said pattern-supporting table being pivotally suspended from said work-supporting tables, guide-shoes carried by said pattern-supporting table on opposite sides thereof, positively-driven coincidently-operating friction sprocket-belts operating through said guide-shoes, and springs arranged to oppose the action of said friction-belts upon said table, as and for the purpose set forth.

85

26. In a carving-machine, and in combination with tracing and cutting mechanism and means for operating the same, a work-supporting table, a pattern-table suspended therefrom, means for yieldingly supporting said work-table, independent means connected to said tables and arranged to support a portion of the weight of such tables, and means for adjusting said independent means whereby said independent means supports a portion of the weight of the tables in proportion to the weight of the pattern and work placed thereon, as and for the purpose set forth.

105

27. In a carving-machine, and in combination with tracing and cutting mechanisms, and means for operating the same, pattern and work supporting tables, springs for yieldingly supporting the same, independent tension mechanism connected to the tables and arranged to exert a supporting tension thereon, and means for adjusting the tension applied to said tables by said independent tension mechanism in proportion to the weight of the pattern and work, as and for the purpose set forth.

110

28. In a carving-machine, and in combina- 115

120

125

130

- tion with tracing and cutting mechanisms, and means for operating the same, pattern and work supporting tables, springs arranged to support said tables, racks connected to said 5 tables, gears coöperating with said racks, auxiliary springs, and adjustable connections between said auxiliary springs and gears, as and for the purpose set forth.
29. In a carving-machine, and in combination with tracing and cutting mechanisms, and means for operating the same, work and pattern supports, springs for yieldingly sustaining said supports, auxiliary springs arranged to apply their tension to aid in sustaining said 10 supports, and including turnbuckles, whereby the tension of said auxiliary springs may be adjusted according to the weight of the work and pattern, as and for the purpose set forth.
30. In a carving-machine, and in combination with tracing and cutting mechanisms, and means for operating the same, a work-support, including sleeves, guide-rods upon which said sleeves operate, springs for supporting said 15 sleeves, racks carried by said sleeves, gears arranged to engage said racks, a crank-arm for operating said gears, auxiliary springs, and adjustable connections between said auxiliary springs and crank-arms, as and for the purpose set forth.
31. In a carving-machine, and in combination with tracing and cutting mechanisms, and means for operating the same, a work-support, including a frame having sleeves, guide-rods 20 upon which said sleeves are mounted, springs for supporting said frame upon said rods, a pattern-support pivotally suspended from said work-support, friction drive mechanism arranged to engage said pattern-support when the latter is moved laterally, and operating to move said pattern-support against the action of said springs, auxiliary tension mechanism arranged to be applied to said supports, and including a scale attachment, and means for 25 adjusting said auxiliary tension mechanism, as and for the purpose set forth.
32. In a carving-machine, and in combination with tracing and cutting tools and means for operating the same, work and pattern supports mounted for vertical movement toward and from the tracing and cutting tools, centers carried by said supports, tailpieces coöperating with said centers, removable supporting-bars for said tailpieces, means for coincidently rotating said centers, and means controlled by the engagement of the tracing-tool 30 and pattern for moving the work and pattern supports toward and from the tracing and cutting tools, as and for the purpose set forth.
33. In a carving-machine, and in combination with tracing and cutting tools, work and

pattern supports mounted for vertical movement toward and from said tracing and cutting tools, centers carried by said supports, removable tailpieces coöperating with said centers, gearing for coincidently driving all of said centers, means whereby said gearing may be applied to said centers to produce both right and left hand work from the same pattern, and means controlled by the engagement 65 of the tracing-tool with the pattern for moving the work and pattern supports toward and from the tracing and cutting mechanism, as and for the purpose set forth.

34. In a carving-machine, and in combination with tracing and cutting mechanism, and means for operating the same, a work-table, a pattern-supporting table connected thereto, shoes carried by said pattern-table, friction-belts, means for driving the same, said shoes 70 being made in sections and arranged to be clamped together to hug said belts, and means for yieldingly opposing the action of said belts upon said tables, as and for the purpose set forth.

35. In a carving-machine, and in combination with tracing and cutting mechanism, and means for operating the same, a work-supporting table, a pattern-supporting table suspended therefrom, shoes carried by said pattern-table, suitably-driven friction-belts arranged 80 to be embraced by said shoes, and means for yieldingly opposing the action of said belts upon said tables, as and for the purpose set forth.

36. In a carving-machine, and in combination with tracing and cutting mechanism, and means for operating the same, a work and pattern support having racks and shafts arranged on opposite sides of said support and carrying 90 gears at each end arranged to engage said racks, whereby when either of said shafts is rotatively moved to raise or lower said support all of said gears are operated in unison, as and for the purpose set forth.

37. In a carving-machine, and in combination with tracing and cutting mechanism, and means for operating the same, a work and pattern support having guiding-sleeves, guide-rods therefor, racks carried by said sleeves, 100 shafts arranged in parallel relation on opposite sides of said supports, and gears mounted on each end of each shaft and engaging said racks, as and for the purpose set forth.

In witness whereof I have hereunto set my 115 hand, this 20th day of January, 1903, in the presence of the subscribing witnesses.

FRANKLIN P. BURKHARDT.
